UNITED STATES PATENT OFFICE.

STEN ERIC LINDVALL, OF ALTONA, GERMANY.

PUSH-BUTTON SWITCH.

Application filed May 24, 1924. Serial No. 715,616.

To all whom it may concern:

Be it known that I, STEN ERIC LINDVALL, subject of Sweden, residing at Altona, Germany, Eimsbüttlerstrasse 8, have invented 5 certain new and useful Improvements in a Push-Button Switch, of which the following is a specification.

The present invention has for its object to construct a push button switch which is 10 durable and can be manufactured at comparatively small costs. This push button switch can be constructed as a single contact breaker as well as a multiple way contact breaker. The push button switch comprises 15 an axially movable, non-rotatable spirally twisted member which on its reciprocative movement transmits motion to a slotted operating member having ratchet teeth to operate a movable contact piece. 20 Ratchet teeth are also provided on the casing to lock the contact piece in position after making or breaking the connection of a circuit. The last named ratchet teeth correspond in number to the ratchet teeth of the 25 operating member.

The construction can be carried out in different ways. Of particular advantage is the construction which is hereafter described and illustrated. In this mode of construction 30 there is the advantage, that the movable contact piece which has springy arms to make contact with fixed contact pieces is not by these arms themselves locked in position after every operation and therefore 35 fore does not slide over said ratchet teeth so that these arms of the contact piece are not so soon worn out or do not lose their flexibility, but in the construction shown by way of example special spring 40 pawls are used which can be made of steel and are not liable to lose the flexibility and therefore will never fail in operation.

Fig. 1 of the drawings is a section of the 45 push button switch constructed according to the present invention, and

Fig. 2 is a plan of the switch the upper part or cover being removed.

The push button switch comprises a casing 50 consisting of the lower member *a* and the upper member *b* forming a cover. The push button proper *c* is guided within a suitably shaped opening *d* in the cover and has a shaft *e* of a flat cross section and spirally twisted. The utmost end *f* of this shaft 55 is guided in a slot *g* in the bottom of the casing member *a*. Connecting terminals *h*

are provided for connecting the conductors and correspond in number to the electric circuits to be switched. In the construction shown two terminals are provided for a one way switch. They are electrically connected with the fixed contact pieces *i* the movable contact piece *k* having two arms *k'* adapted to make contact with the contact pieces *i* bears with its central disk shaped part *k²* 60 against a central boss *a'* on the bottom of the lower casing member *a*. The central disk-shaped contact piece *k* in the construction shown by way of example has perforated flanges *m* through which projects a 65 yoke *n* preferably made of steel wire, and the prongs *o* of which yoke are bent to form pawls adapted to slide over and to be engaged or locked in position by ratchet teeth *p* preferably formed on the bottom of the 70 lower casing member *a*. On the disk-shaped contact piece *k* a dish-shaped operating member *q* is adapted to slide having a slot *r* corresponding to the cross section of the shaft *e* of the button *c*. The lower rim of 75 the dish-shaped operating member is serrated to form ratchet teeth *u* corresponding in number to the ratchet teeth *p* formed in the bottom of the lower casing member *a*. To properly guide the disk *k* a circular bushing *s* is let into the boss *a'*, the disk *k* being 80 provided with a corresponding central opening, the yoke *n* being bent in a central part to surround the bushing *s*, the curved part lying flat on the disk *k*. A spiral spring *t* 85 is interposed between the push button proper *c* and the operating member *q*, tending to press the operating member *q* down on the disk *k* to engage by its teeth the yoke *n*, when the push button *c* is pressed down. 90 By so pushing the button down the spirally twisted shaft *e* causes the operating member *q* to rotate for the angle of the pitch of the teeth *u* and *p* respectively, the pawls *o* sliding from one tooth *p* over the next following tooth *p* to be engaged by this tooth when the described movement is completed, thus locking the movable contact piece *k* either 95 to make or to break contact with the fixed contact pieces *i*. On the return movement of the push button *c* the operating member *q* will be rotated backwards to its initial position, its teeth *u* hereby sliding over the yoke *n* and being held in contact therewith by the spring *t*. Thus on every pushing 100 down of the button *c* the movable contact piece *k* will be rotated for the angle of the 105

pitch of the teeth either to make or to break contact.

I claim:

1. A push button switch comprising a casing, contact pieces attached to the sides of the casing and a rotatable contact piece adapted to make and break contact between the said fixed contact pieces, a spring pressed push button having a flat spirally twisted shaft prevented from rotation by being guided in a slot in the bottom of the casing, a slotted operating member engaged by said spirally twisted shaft to be rotated thereby, when pushing down the button, ratchet teeth on the bottom of the casing and ratchet teeth on the said operating member, corresponding in number to the first named ratchet teeth, a spring pawl carried by the rotatable contact piece and adapted to be engaged by the first named ratchet teeth and to slide over the second ratchet teeth so as to be rotated about an angle corresponding to the pitch of the teeth by pushing inwardly the button and then locked in position when the said operating member returns into its original position on the backward movement of the button by its spring. 35
2. A push button switch comprising a casing, contact pieces attached to the sides 40
- 10
- 15
- 20
- 25
- 30

of the casing and a rotatable contact piece adapted to make and break contact between the said fixed contact pieces, a spring pressed push button having a flat spirally twisted shaft prevented from rotation by being guided in a slot in the bottom of the casing, a slotted operating member engaged by said spirally twisted shaft to be rotated thereby, when pushing down the button, ratchet teeth on the bottom of the casing and ratchet teeth on the said operating member, corresponding in number to the first named ratchet teeth, a spring pawl carried by the rotatable contact piece and adapted to be engaged by the first named ratchet teeth 45 and to slide over the second ratchet teeth so as to be rotated about an angle corresponding to the pitch of the teeth by pushing inwardly the button and then locked in position when the said operating member returns into its original position on the backward movement of the button by its spring. 50

3. A push button switch according to claim 2, characterized in this that two spring pawls forming prongs of a yoke are carried by the rotatable contact piece, the middle part being bent suitably guided to prevent rotation of the yoke, when the prongs slide on the locking ratchet teeth. 55

STEN ERIC LINDVALL.
